UNITED STATES PATENT OFFICE

FRIDOLIN POLZER, OF NORWALK, CONNECTICUT, ASSIGNOR TO THE E. H. HOTCHKISS COMPANY, OF NORWALK, CONNECTICUT, A CORPORATION OF CONNECTICUT

DESK STAPLING MACHINE

Application filed February 9, 1929. Serial No. 338,832.

This invention relates to stapling machines and more particularly to an improved means for clinching the staples, and has for an object to provide a clinching means for stapling machines which will so clinch the staple that it will lie flat against the surface of the work thus overcoming the objection to the manner in which the staples are set by the ordinary stationary curved anvil which leaves the staples curved so that they project an undesirable distance above the face of the work.

It is also an object of the invention to provide a stapling machine in which the staples may be set in different manners by shifting 15 or changing the clinching means.

With the foregoing and other objects in view, the invention consists in certain novel features of construction, combinations and arrangements of parts as will be more fully disclosed in connection with the accompanying drawing. In this drawing,

Fig. 1 is a side elevation and partial section of a stapling machine provided with my improved construction.

Fig. 2 is a front elevation thereof.

Fig. 3 is vertical section through the stapling means showing the manner of clinching the staple.

Fig. 4 is a vertical section through the base just forwardly of the clinching anvils, showing them in the ordinary position of rest.

Fig. 5 is a similar view showing the use of two anvils having a different effect on the staple.

Fig. 6 is a similar view showing still another arrangement of the anvils.

Fig. 7 is a similar view showing a slightly different means for operating the anvils.

Fig. 8 is a similar section showing how the anvils may be arranged to set a temporary staple.

Figs. 9 and 10 are end and side elevations respectively showing the anvils, and

Fig. 11 is a section through a card or similar article showing how the staple may be applied for hanging the card on a wire or similar support.

The machine comprises the usual base 12 to which is pivoted the housing 13 at 14 carrying the vertically reciprocable plunger 15

for driving the individual staples 16. In the present machine these are wire staples either round or more or less flat and fed on the guide bar 17 by a slide or follower 18 drawn forward by a coil spring 19. The plunger is 55 operated by the hand knob 20 and is normally held in the upper position by a spring 21 either outside or inside the housing as desired. This plunger may be of the type disclosed in my prior Patent #1,588,990, June 15, 1926. It will, of course, be understood that when the plunger is depressed it carries down the forward staple and drives it through articles to be stapled, such as sheets of paper 22, placed under the housing and on top of the anvil. 60

My improved anvil construction is 65

mounted in a block 23 carried by the base 12 under the forward end of the housing. This block has a transverse slot in which

are mounted the movable anvils or staple clinching means. In Figs. 2 and 3 there

are two anvils 24 each pivoted in the block at 25 on opposite sides of the plunger, the pins 25 being removable and extending

transversely through the block and have 70 knurled heads 26 to be grasped by the operator for inserting or removing these pins.

Mounted below the base 12 is a resilient plate 27 which is secured at its rear end to the under side of the base by any suitable

means, such as the screws 28. This plate is curved so that at its forward end it is normally spaced from the lower surface of the base, as shown in Figs. 1 and 2. In other

words the base is supported a suitable distance above this plate and the forward ends

of the housing and plate are movable relative to each other. Coil springs 29 may also

be placed between the base and this plate to assist the plate supporting the base but

80 permit the relative movement between the two. Carried by the base plate 27 is an upright block 30 which is recessed at its upper

edge and on which the pivoted anvils 24 rest. When the machine is not operating

90 the elements are in the position of Figs. 1 and 2. If now it is desired to staple sheets

of paper 22 for instance the forward end of the housing is raised and the paper is inserted beneath the housing on top of the

100

block 23. If now a blow of the hand is struck on the knob 20 the plunger 15 is depressed forcing the prongs of the forward staple through the work, it being understood that the staple is of substantially inverted U-shape with the prongs depending from the body. Continued movement of the plunger downwardly forces the forward end of the base 12 and the block 23 carrying the anvils 24 downwardly toward the plate 27 and the upright member 30 because downward movement of the plunger relative to the housing is limited by any suitable means, such as the shoulder 43 on the plunger engaging the stop 44 in the housing. This causes the upper ends of the member 30 to push upwardly on the lower sides of the anvils 24 and swing them about their pivots to the horizontal position of Fig. 3. While they swing to this position the anvils engage the prongs of the staple and fold them against the under side of the work, as shown in Fig. 3. When the machine is in the position of rest the upper edges 31 of these anvils are inclined downwardly and inwardly, as shown in Fig. 2, so that the ends of the prongs are bent slightly inward as they hit these upper edges and then are pressed tightly against the under side of the work as the anvils are swung upwardly to the position of Fig. 3. It is preferred also that the upper edges of these anvils be grooved, as shown at 32, to better hold the staples in proper position. It will be seen from this operation the prongs of the clinched staple shown at 16', Fig. 3, are pressed flat against the under side of the work and are not left curved as is the ordinary operation of a machine using a stationary anvil, because the stationary anvil in order to properly bend the prongs must have curved bending surfaces and they, therefore, leave the prongs curved so that they project an undesirable amount above the surface of the work. With this present construction, however, the prongs are laid perfectly flat giving a much better clinching effect and as the staple does not project so far from the surface of the work they are much less liable to catch on other objects.

Figs. 4 to 8 inclusive are views showing different arrangements which may be used for the anvils to secure different effects. In Fig. 4 the anvils are practically the same as those of Fig. 3 but instead of the single operating block 30 of Fig. 3 there is an upwardly extending post 33 for each anvil. The operation is the same, however, as Fig. 3 and the staple 16' is set in the same manner.

In Fig. 5 one of the anvils, indicated at 34, is of less height than the other anvil so that when the anvils are forced upwardly one prong 35 folded by the anvil 24 is pressed against the under side of the work in the

usual manner, but the other prong 36 is not forced up against the work by the anvil 34 but is only partly clinched leaving a hook. Therefore, if the prong 35 is clinched through a card 37, for instance, as shown in Fig. 11, the prong 36 forms a hook by which the card or a handkerchief or similar article may be suspended from a wire or other suitable support, for display purposes for example.

In the arrangement of Fig. 6 somewhat the same effect is secured as in the arrangement of Fig. 5. Here, however, instead of having the second anvil pivoted it may be mounted on the upright base plate 27. In other words the upright 38 may have a grooved inclined upper wall 38' which acts to bend in the prong 36 only part way.

In Fig. 7 the result is practically the same as that of Figs. 1 to 4. Here the free ends of the anvils 39 rest on the top of a block 40 carried by the base plate 27 so that as the base 12 moves downwardly the block 40 forces the anvils up to clinch the staple 16', as shown in Figs. 3 and 4.

Fig. 8 illustrates how the anvil may be arranged to clinch the staple for a temporary bond. That is, the prongs of the staple are so set that the staple may be easily removed and the staple is not as permanently set as in the other forms. It will be noted that the block 23 is provided with three transverse openings in any one of which the pins 25 may be placed. If the pins are placed in the two outer openings 41 the anvils are inclined downwardly and inwardly toward each other so that they operate to bend both prongs of the staple inwardly toward each other. If, however, one of the pins 25 for one of the anvils is placed in the central opening 42, as indicated in Fig. 8, both anvils will be inclined in the same direction, and therefore, when the machine is operated both prongs will be bent in the same direction. That is, one prong 35 will be bent inwardly by the left hand anvil as in the other forms while the other prong 43 will be bent outwardly by the other anvil making a staple much more easy to remove from the articles stapled if it is desired to unstaple them.

Therefore, with the construction arranged as illustrated different shapes of anvils may be used to have different effects on the prongs of the staples, or the anvils may be of different arrangements to have different effects on the prongs of the staples.

Having thus set forth the nature of my invention, what I claim is:

1. In a stapling machine, a base, a housing pivoted to the base, a reciprocable plunger carried by the housing, an anvil carried by the base and movable toward the plunger to force the free end of a staple toward the under side of the articles to be stapled, means below the base on which the base rests and

movable toward the base, means carried by the latter means to lift said anvil on depression of the plunger, and spring means to normally hold the base above the carrier for the anvil operating means.

5 2. In a stapling machine, a base, a housing pivoted to the base, a reciprocable plunger carried by the housing, one or more pivoted anvils carried by the base, means below the base on which the base rests movable toward the base and having means to swing the anvil or anvils toward the plunger by said movement, and spring means tending to separate the base and said first mentioned means.

10 15 3. In a stapling machine, a base, a housing hinged to the base, a vertically reciprocable plunger carried by the housing, movable anvils below the plunger and adapted to cooperate therewith to set the staples, and a sub-base below and supporting the base, the base being movable toward the sub-base to shift the anvils towards the plunger.

20 25 4. In a stapling machine, a base, a housing hinged to the base, a vertically reciprocable plunger carried by the housing, a pair of pivoted anvils carried by the base below the plunger and adapted to cooperate therewith to set a staple, and means below the base to support said base and movable to swing the 30 anvils toward the plunger.

25 35 5. In a stapling machine, a base, a housing hinged to the base, a vertically reciprocable plunger carried by the housing, a pair of pivoted anvils carried by the base below the plunger, a subbase below the said base normally spaced therefrom and movable toward it, and means carried by the subbase to swing the anvils toward the plunger by said movement.

40 45 6. In a stapling machine, a base, a housing hinged to the base, a vertically reciprocable plunger carried by the housing, a pair of movable anvils below the plunger and adapted to cooperate therewith to set the staples, a subbase below the first base, resilient means to hold it normally spaced therefrom, and means carried by the subbase to shift the anvils toward the plunger by said movement.

50 65 7. In a stapling machine, a base, a housing hinged to the base, a vertically reciprocable plunger carried by the housing, a pair of anvils pivoted to the base below the plunger and adapted to cooperate therewith to set the staples, a subbase below the first base, resilient means to normally hold the subbase spaced from the base, and upright means on the subbase to engage under the anvils and swing them toward the plunger on relative movement of the base and subbase toward each other.

60 65 8. In a stapling machine, a base, a housing hinged to the base, a vertically reciprocable plunger carried by the housing, a plurality of anvils, pivots for the anvils, said base being provided with a plurality of means for

receiving said pivots to support the anvils and arranged to support the anvils in different relations to the plunger to have different effects on the staple, a subbase normally spaced below the first base and movable toward it, and means carried by the subbase to swing the anvils on their pivots.

70 75 9. In a stapling machine, a base, a housing pivoted to the base, a reciprocable plunger carried by the housing, a pair of pivoted anvils carried by the base under the plunger and adapted to cooperate therewith to fold the ends of a staple against the under side of the work, and a sub-base below and supporting the base movable toward said base having means to swing the anvils toward the plunger by said movement.

In testimony whereof I affix my signature.
